UNITED STATES PATENT OFFICE.

ADAM BRENZINGER, OF NEW YORK, N. Y., ASSIGNOR TO A. BECK & CO.,
OF SAME PLACE.

QUILTING-MACHINE.

SPECIFICATION forming part of Letters Patent No. 289,884, dated December 11, 1883.

Application filed September 7, 1883. (No model.)

To all whom it may concern:

Be it known that I, ADAM BRENZINGER, of the city, county, and State of New York, have invented certain new and useful Improvements in Quilting-Machines, of which the following is a specification.

This invention has reference to certain improvements in quilting-machines, whereby not only diagonally-intersecting lines of stitches, which form the so-called "diamonds," but also a number of different ornamental patterns, may be produced by the same mechanism.

The invention consists, essentially, of a vertically-reciprocating needle-bar having a series of needles arranged in three rows, the intermediate row having twice as many needles as the first and third rows, with mechanism by which the fabric is fed forward and simultaneously in lateral direction.

The invention consists, secondly, of the construction of the needle-bar in which three rows of needles are arranged, of which the intermediate row has twice as many needles as the first and third rows, which are located diagonally in line with and equidistantly from the needles of the first and third rows, all the needles being supported by two parallel needle-bars, the front bar of which is provided with slots to regulate the set-screws of the intermediate row of needles.

In the accompanying drawings, Figure 1 represents a front elevation of my improved quilting-machine. Fig. 2 is a plan of the same. Fig. 3 is a diagram showing the relative arrangement of the needles on the needle-bar. Fig. 4 is an end elevation of the quilting-machine. Figs. 5 and 6 are respectively a detail plan and a side view of the needle-bar, the latter figure having a part broken away. Figs. 7, 8, and 9 are diagrams showing different patterns that can be stitched on my improved quilting-machine.

The essential feature of my invention consists of the construction of the needle-bar, which I have shown in connection with a quilting-machine constructed on the type shown in the patent granted to August Beck, No. 279,632, dated June 19, 1883. In this machine a series of organized sewing mechanisms are

arranged on a carriage, B, moving on anti-friction rollers *b b* of a horizontal supporting-frame, A.

To the carriage B an intermittent laterally-reciprocating motion is imparted by suitable mechanism, which is fully described in the patent referred to.

The fabric is fed in the usual manner over the cloth-table by intermittently-actuated feed-rollers D D. The needle-bar C is vertically reciprocated by suitable mechanism, and provided with a series of needles, which are arranged in three distinct rows, one behind the other. The middle row contains twice as many needles as either the first or third row, which needles are diagonally in line with those of the outer rows and equidistantly from the same.

For supporting the needles in the order described, the needle-bar is made of two parallel bars, *d d'*, of which the rear bar is made thicker than the front bar, both being provided with grooves *e* for the shanks of the needles, and with set-screws *f f*, by which the needles are retained in the grooves *e e* of said bars, as shown in Figs. 5 and 6. The rear bar, *d*, serves to support the needles of the second and third rows, while the front bar supports only the needles of the first row. The front bar, *d'*, is provided with inclined slots *d'*, so that the set-screws of the needles of the second row can be easily adjusted from the front of the needle-bar. The shuttles and shuttle-races are arranged below the cloth-table, and are made to correspond to the positions of the needles. They are not shown in the drawings, as they are made in the usual manner and require no special description.

When the fabric to be quilted is fed forward by the feed-rollers D and the carriage B, that supports the organized sewing mechanisms, moved simultaneously in a lateral direction, diagonal lines of stitches are formed on the material to be quilted. By the lateral motion of the carriage in opposite directions, the direction of the diagonal lines of stitches is reversed, whereby each needle produces a zigzag line of stitches which meets the zigzag lines of stitches of the adjoining needles at the angles of said lines, so as to impart thereby to the fab-

ric the character of intercrossing diagonal lines of stitches that form regular diamonds, as shown in Fig. 7.

If a suitable pattern-cam is employed, by which the lateral motion of the fabric is interrupted at certain intervals, a number of different designs, such as are shown in Figs. 8 and 9, can be produced, by which variegated effects may be imparted to the quilted fabrics.

10 Quilted linings of different designs can thereby be produced in a quick, economical, and effective manner by the conjoint action of mechanisms for moving the fabric and the action of the needle-bar having three independent rows of needles.

I am aware that a quilting-machine having a needle-bar with two rows of needles, of which the second is behind the first row and alternating therewith, is well known, and I do not claim the same.

Having thus described my invention, I claim as new and desire to secure by Letters Patent—

1. In a quilting-machine, the combination of a vertically-reciprocating needle-bar having a series of needles arranged in three rows, one behind the other, the intermediate row having twice as many needles as the first or third row, the needles of said intermediate row being set in the diagonal line with and equidistant from the needles of the first and third rows, devices

for feeding the fabric forward beneath the needles, and mechanism whereby laterally-reciprocating motion is imparted to the entire sewing mechanisms, substantially as set forth.

2. In a quilting-machine, a needle-bar constructed with three rows of needles, one behind the other, the intermediate row having twice as many needles as the first or third row, which needles are located in the diagonal line with and equidistant from the needles of the first and third rows, substantially as specified, in combination with means for operating the needle-bar.

3. In a quilting-machine, the combination of a bar adapted to receive a set of needles, means for clamping said needles thereto, a supplemental bar adapted to receive two sets of needles, and set-screws for clamping the same to either side of said supplemental bar, the first bar being provided with slots, whereby access may be had to the set-screws between the bars for adjusting the same, substantially as described.

In testimony that I claim the foregoing as my invention I have signed my name in presence of two subscribing witnesses.

ADAM BRENZINGER.
